UNITED STATES PATENT OFFICE.

PHILEMON O. DICKINSON, OF NEWARK, NEW JERSEY.

DESIGN FOR A POCKET-BOOK, &c.

SPECIFICATION forming part of Design No. 25,821, dated July 21, 1896.

Application filed June 1, 1896. Serial No. 593,934. Term of patent 31 years.

To all whom it may concern:

Be it known that I, PHILEMON O. DICKINSON, a citizen of the United States, residing at Newark, in the county of Essex and State 5 of New Jersey, have invented and produced a new and original Surface Design for Pocket-Books and Similar Articles, of which the following is a specification, reference being had to the accompanying drawing, which illustrates the design.

The present design relates particularly to metallic surface work applied to the edge and sides of a sheet or flap, such as the flap or side of a pocket-book or similar article.

15 In the drawing, the figure shown represents a face or plan view of the design as the same might be applied to the flap or side of a pocket-book.

The style of the design is a modernized 20 adaptation of the rococo order.

The essential part of the design consists of a border A, B, and C, running between two corners of the article to which it is applied and a short distance away from the corners on their other sides or edges. This border is 25 composed of rococo design work, the prominent features of which are the corner shell designs D and E, together with the centrally-arranged shell shield F, which is superimposed by the cupid and psyche figures G. 30

The essential features of the design are those above set forth.

What is claimed as new is—

The herein-described design for pocket-books and similar articles, substantially as 35 shown and described.

PHILEMON O. DICKINSON.
